UNITED STATES PATENT OFFICE.

GIP CORTEZ, OF TIPTON, CALIFORNIA.

RESTRAINING APPARATUS.

1,417,230.

Specification of Letters Patent. Patented May 23, 1922.

Application filed December 11, 1920. Serial No. 430,029.

To all whom it may concern:

Be it known that I, GIP CORTEZ, a citizen of the United States, and a resident of Tipton, in the county of Tulare and State of California, have invented certain new and useful Improvements in Restraining Apparatuses, of which the following is a specification.

This invention is a restraining apparatus especially adapted for use in connection with pigs.

An important object of this invention is to provide a restraining apparatus or holder which may be employed for safely holding pigs while being operated upon so that the pigs will not become injured as the result of rough treatment, at the hands of the attendant.

A further object of the invention is to provide a restraining apparatus for the purpose set forth which may be operated entirely by one man thereby dispensing with the necessity of employing several attendants to hold the pig when operated upon.

A further object of the invention is to provide a restraining apparatus for pigs and the like which may be readily and conveniently adjusted for use in connection with animals of various sizes.

A further object of the invention is to provide a restraining apparatus of the class described simple to adjust, efficient in use and cheap to manufacture.

Other objects and advantages of the invention will be apparent during the course of the following description.

In the accompanying drawings forming a part of this application and in which like numerals are employed to designate like parts throughout the same,

Figure 1 is a plan view of the improved restraining device,

Figure 2 is a side elevation of the same,

Figure 3 is an end elevation of the same,

Figure 4 is a detail sectional view through the same, the view illustrating the means for holding one of the movable portions of the apparatus in position,

Figure 5 is a perspective of a latch embodied in the invention.

In the drawings wherein for the purpose of illustration is shown the preferred embodiment of the invention, the numeral 10 generally designates a platform which as illustrated in Figure 3 is mounted upon a pair of supports 12 having their upper lon-

gitudinal edges inclined so as to tilt the platforms transversely.

A pair of spaced parallel brackets 14 are extended across the platform 10 and these 60 brackets 14 have their end portion formed with loops 15 connected to the platform or base 10 by means of screws 16 or other suitable fastening members. Each bracket 14 is formed from a length of metal having one 65 end portion bent at an angle to provide a standard 17 having one end portion extending laterally and looped to form an attaching member 18 secured to the platform by a screw or other suitable fastening device 20. 70 Bracing rods 21 are connected to the base as indicated at 22 and are connected at their upper ends to the uppermost portions of the brackets 14 so as to strengthen and support the bracket.

What might be termed an operating table 24 is mounted on the pair of spaced brackets 14 and serves as a supporting means for the pigs while the latter are being operated upon. The table 24 comprises a bottom wall 80 26 rigidly secured to the brackets 14 by means of fastening members 28. The table 26 which is formed from a sheet of metal has one longitudinal edge portion bent upwardly to constitute a stationary side wall 85 30 which is supported by a pair of spaced parallel triangular bracing members 32. The lower portions of the bracing members 32 are formed with laterally projecting flanges 34 secured to the platform 10 by 90 means of fastening devices 36. The upper portions of the triangular bracing members 32 are also formed with flanges 36 which are secured to the stationary platform by means of rivets or other fastening devices 37.

The operating table 24 also consists of a bottom wall 38 slidable with relation to the stationary bottom wall 26 and having an inclined side wall 39. The end portions of the stationary bottom wall 26 are provided 100 with flanges 40' which extend beneath the end portions of the sliding bottom wall 38 so as to guide the same with relation to the stationary bottom wall 26. The stationary and movable sections of the table constitute 105 a run-way in which a pig is adapted to be arranged so that the same may be held in position while being operated upon.

When the animal is arranged within the run-way its head is positioned beneath a 110 head confining device 40 which consists of telescopic sections 41 and 42 slidable with

relation to each other through the medium of guide flanges 43 formed along the edges of the section 41 and extending beneath and contacting with the edge portions of the section 42. The section 42 of the head confining member 40 is secured to the movable side wall 39 by means of fastening devices 43 which are extended through an attaching flange 44 and the adjacent portion of the 10 movable side wall. The head confining device 40 arranged at the forward portion of the run-way is inclined with respect to the bottom walls of the table, since the portions of the walls 30 and 39 to which the head 15 confining device is attached are beveled or cut off. With reference to Figure 3 it will be observed that the lower portion of the head confining device 40 terminates at a point spaced above the bottom wall 26 so 20 as to provide an air space 46 which permits the animal to freely breathe when confined within the run-way.

The movable bottom wall 38 is provided with a pair of guide sleeves 50 which slidably receive the brackets 14 and constitute a means whereby the movable section of the 25 table is guided when moved along the brackets.

In order that the movable section of the 30 table might be operated along the brackets, I have provided the upstanding side wall 39 of the same with hand grips 52 which are located within convenient reach of the operator and which may be engaged and drawn 35 in the direction of the operator when it is desired to increase the space between the side wall 39 and the stationary side wall 30. It might be stated that prior to introducing the pig into the run-way the inclined side 40 wall 39 is moved outwardly or away from the stationary side wall 30 so as to permit of the ready entrance of the pig to the run-way. The movement of the bottom wall 38 and the side wall 39 is limited by reason of 45 a pair of spring latches 54 which traverse the upper side of the brackets and which are adapted to be engaged with teeth 56 formed on the upper sides of the brackets. With reference to Figure 4 in particular it 50 will be noted that the latches are of spring metal and are attached to the underside of the movable section 38 through the medium of rivets or other suitable fastening devices. The thumb pieces 60 of the latches 54 terminate adjacent the grips 52 so as to be within 55 convenient reach of the operator. When it is desired to move the bottom wall 38 to the left in Figure 4 the operator may grasp the hand grips 52 and elevate the 60 thumb pieces 60 of the latches 54 so as to free the latches from engagement with the teeth formed on the upper sides of the brackets 14 whereupon the movable section of the table may be freely positioned. The 65 movement of the bottom wall 38 is limited

by a pair of stop elements 62 which may be adjusted along the brackets 14 by small set screws 63 or the like.

The movable section of the table is braced with relation to the stationary section by means of a telescopic brace 66 which consists of a pair of slidably connected tubes having their ends secured to the side walls 30 and 39 as indicated at 67. When preparing the run-way for the pig, the movable section is moved upwardly along the brackets 14 so as to increase the space between the side walls 30 and 39. A gate 68 is formed in the movable side wall and is hingedly supported as indicated at 70 so 75 that the same may be swung downwardly into contact with one of the brackets 14 when it is desired to make the opening in the run-way as large as possible for the entrance of a pig. The pig is introduced to 80 the run-way with more or less of a side sweep and therefore the section of the side wall 39 which constitutes the gate 68 must be swung downwardly. When the animal is arranged in the run-way its jaw is held 85 in place by the jaw confiner 40 and its left side rests against the stationary side wall 30. The gate 68 is now quickly closed and the fore legs of the pig are fastened with 90 the chain 71 slidable through an opening 52 in the stationary side wall 30. Upon fastening the fore legs of the pig with the chain 71 the chain may be drawn up into the narrow slot 73 in the stationary side wall 30 so that the pig may be securely held in 95 position. The rear end of the chain is formed with a loop 74 which is of a greater diameter than the opening 72 so that the 100 accidental loss of the chain is prevented.

The hind legs of the pig may now be separately engaged by a pair of chains 76 anchored to the side walls by clips 77. The chains 76 are slidable through openings 78 formed in the side walls of the run-way and are provided with retaining loops 80 similar 110 to the loops 74. In order that the chains 76 might be held in an adjusted position I have provided slots 81 which communicate with the openings 78 and which are adapted to receive the chains 76. 115

After the side wall 39 has been moved downwardly into contact with the right side of the animal's body the desired operation may be performed in an expeditious manner without the necessity of employing attendants to the operator.

When the desired operation has been performed and when the antiseptic has been administered the side wall 39 may be moved outwardly so as to permit of the removal of 125 the pig from the run-way. The apparatus may be now prepared for the next operation by throwing the gate 68 downwardly and by properly positioning the chains 76 and 71. After engaging the hind legs of the pig, the 130

chains 76 may be wound about a pair of adjustable posts 88 carried by the side walls of the table and slidably through guiding elements 89.

- 5 With reference to the foregoing description taken in connection with the accompanying drawings it will be observed that the table in being tilted transversely is so arranged that the animals may be conveniently operated upon. The operator stands adjacent the movable side wall 39 and since the rear end of the gate is inclined, the operator will have free access to the animal. The gate 68 is adapted to overlap the adjacent portion of the side wall 39 and is provided with a spring actuated latch 90 which is adapted to engage a keeper 92 carried by the movable side wall 39.
- 10 It is to be understood that the form of the invention herewith shown and described is to be taken as a preferred example of the same and that such minor changes in the arrangement and construction of parts may be made as will remain within the spirit of what is claimed.
- 15 Having this fully described my invention what I claim is:—

1. An animal restraining apparatus comprising a plurality of inclined brackets, a stationary section and a movable section mounted upon said brackets, spring latches carried by said movable section and having means engaging said brackets whereby to hold the movable section in position, said sections being provided with upstanding side walls, one of the side walls being provided with a hinged portion defining a gate, means to lock said gate to the side wall in a set position, a telescoping base inclusive of a pair of slidably connected sections having their outer ends joined to said side walls, a head confining member inclusive of a pair of slidably connected flat metallic sections adapted to flatly contact with the top of an animal's head, the outer ends of the sections of said head confining member being secured to the ends of said side walls, and chains carried by said side walls to engage the limbs of an animal.

2. An animal restraining apparatus comprising a run-way inclusive of a pair of overlapping bottom walls slidable with relation to each other, a pair of upstanding side walls secured to the bottom walls, and means to support the run-way in a transversely inclined position, and head restraining means carried by the ends of said side walls and constituting a brace for the side walls.

3. An animal restraining apparatus comprising a transversely inclined run-way inclusive of a pair of slidably connected bottom walls and side walls connected to the bottom walls, the major portion of one of said side walls being hinged, an extensible

bracing device connected to said side walls, and means slidably supporting one of said bottom walls.

4. A restraining device for animals comprising a stationary bottom wall, a sliding bottom wall associated with said stationary bottom wall, side walls connected to said bottom walls, an extensible bracing device connected to said side walls, one of said side walls being provided with a hinged section, means rigidly supporting the stationary bottom wall and slidably supporting said movable bottom wall, and a latch carried by said sliding bottom wall and engaging said supporting means whereby to hold the sliding bottom wall in an adjusted position.

5. An animal restraining apparatus comprising a runway having upwardly extending side walls, a head restraining member attached to said side walls and including flat wide overlapping slidably connected sections, spaced upwardly from the bottom of the run-way and adapted to flatly contact with the top of the animal's head and restraining means carried by said side walls.

6. An animal restraining apparatus comprising a plurality of inclined brackets, a stationary section and a movable section mounted upon said brackets, spring latches carried by said movable section and having means engaging said brackets whereby to hold the movable section in position, said sections being provided with upstanding side walls, one of the side walls being provided with a hinged portion defining a gate, means to lock said gate to the side wall in a set position, a telescoping base inclusive of a pair of slidably connected sections having their outer ends joined to said side walls, a head confining member inclusive of a pair of slidably connected flat metallic sections adapted to flatly contact with the top of an animal's head, the outer ends of the sections of said head confining member being secured to the ends of said side walls, and chains carried by the said side walls to engage the limbs of an animal, the lower edge of said head confining member being spaced upwardly from the bottom of the run-way to define an air passage.

7. A restraining device for animals comprising a pair of slidably connected sections, brackets supporting said sections, a telescopic brace connected to said sections, and a head restraining device connected to said sections and terminating at a point spaced from the bottom of the same thereby forming an air space.

8. A restraining apparatus for pigs comprising brackets, a run-way mounted upon the brackets and comprising stationary and movable sections, means slidably connecting said movable section to said bracket, said brackets being inclined whereby the run-way is inclined transversely, and a latch carried

by said movable section and detachably engaging one of said brackets.

9. A restraining apparatus for pigs comprising stationary and movable sections overlapped and slidable with relation to each other, and said sections being provided with side walls having ends inclined, a head restraining member consisting of flat overlapping portions slidably connected and secured to said side walls, means rigidly supporting said stationary section and slidably supporting said movable section, and a spring latch carried by said movable section

and detachably engaging said supporting means whereby to hold the movable section 15 in an adjusted position.

10. A restraining apparatus for pigs comprising a pair of inclined brackets, a runway mounted upon said brackets and inclusive of slidably connected sections, said 20 brackets being provided with teeth, and spring latches carried by one of said sections and adapted to engage said teeth for securing one of said sections in an adjusted position.

GIP CORTEZ.
